UNITED STATES PATENT OFFICE

RICHARD L. CORNELIUS, OF PASO ROBLES, CALIFORNIA

DISPENSING DEVICE

Application filed December 31, 1928. Serial No. 329,459.

This invention relates to an improved dispensing device which is particularly adapted for use in association with collapsible tubes, such as are employed as containers for tooth paste, shaving cream, cold cream and the like.

Briefly, the invention has reference to a structure embodying a container for the marketed tubes, means in the container for systematically and forcibly ejecting the contents from the tube, and a novel discharge nozzle into and through which the cream is fed in a ribbon like strip for use.

The object is to provide a structure embodying a compact and convenient arrangement of parts so associated and cooperating as to produce a device which will function in a positive and dependable manner and which will fulfill the requirements of an invention of this class in a satisfactory manner.

In the drawings:

Figure 1 is a vertical sectional view through one embodiment of the invention showing the complete association of parts.

Figure 2 is a view similar to Figure 1, the view being taken at approximate right angles to Figure 1.

Figure 3 is a horizontal section taken approximately upon the plane of the line 3—3 of Figure 1.

Figure 4 is a bottom plan view of a removable closure.

Figure 5 is a horizontal section taken approximately upon the plane of the line 5—5 of Figure 1.

Figure 6 is a top plan view of Figure 1.

Figure 7 is a vertical sectional view through a different embodiment of the invention.

Figure 8 is a top plan view of Figure 7.

Figure 9 is a horizontal cross section on the line 9—9 of Figure 7.

Figure 10 is a view taken at right angles to Figure 7.

Figure 11 is a cross sectional view on the line 11—11 of Figure 10.

Figure 12 is a top plan view of Figure 10 with the cover removed.

Attention is first to be confined in the detailed description to Figures 1 to 6 inclusive. In these figures the reference character 13 des-

ignates an open ended tube formed adjacent its opposite end with oppositely pressed circumferentially extending beads 14 and 15, respectively. Those portions of the tube-end beyond the beads constitute annuli 16, having outwardly pressed portions 17 at substantially diametrically opposite points forming keepers. On the lower end is a removable cap 18 and on the upper end is a reversible closure 19. The closure 19 and the cap 18 are interchangeable.

This closure comprises a disc-like cover 20, whose rim portion is pressed inwardly as at 21 to form a panel for reception of a rotary ring gear 22. The teeth of this gear occupy a position shown in Figure 3. The remainder of the rim which fits telescopically over the complementary annulus 16 is provided with diametrically opposite matches 23 of a resilient nature which releasably snap over the keepers 17. This cover is formed with a central opening and an inwardly extending screw threaded collar 24. Threaded through the opening and collar is a nozzle 25 having a socket at its inner end containing a packing ring 26, into which the neck 27 of the conventional collapsible tube 28 is threaded. It is to be noted that the nozzle is provided with a swiveled valve 29, having an outstanding finger grip 30.

Mounted for rotation in suitable bearing brackets 31 within the tube 13 are feed screws 32. There are a pair of these screws and they are located diametrically opposite each other and they are provided at opposite ends with pinions 33 the upper pair of which extend through openings in the grooved portion 21 of the closure 19 as shown in Figure 3 to permit them to mesh with the teeth on the inner periphery of the ring gear 22. Threaded on the feed screw for longitudinal movement are bearing blocks 34 carrying a pair of pressing rollers 35.

These rollers are obviously arranged to engage and compress the end portion 36 of the collapsible container 28. As shown in Figure 1, the nozzle is provided with a discharge slot 37 cooperating with the complementary slot 38 in the valve cap 29.

In operation, the collapsible container 28

is placed within the tube 13 with the end portion 36 between the compressing rollers 35. The neck 27 is threaded into the discharge nozzle 25 as shown in Figures 1 and 2. Then, the valve cap 29 is rotated to bring the slots 37 and 38 into registry with each other. Now, by grasping and turning the ring gear 22, it is obvious that the complementary pinions 33 will be rotated and the feed screws 32 will in turn be rotated. Rotating the ring 22 in the proper direction will gradually feed the blocks 34 upwardly on the feed screws. The result is that the contents of the container 28 will be squeezed out into the nozzle and forced through the slots 37 and 38 in an obvious manner.

It is to be noted that the closure 19 is of a reversible nature. For instance, when the entire contents of the container 28 has been discharged, instead of attempting to feed the blocks 34 down again to the original position, the cap 18 is removed from the lower end of the tube 13 and replaced by the closure 19. Then, the structure is reversed to feed the material from the opposite end thereof.

Substantially the same principle of operation and a similar structure is employed in the embodiment of the invention appearing in Figures 7 to 12, inclusive. Reference being had to these figures, it will be observed that 39 designates an open ended cylinder or tube which, in this instance is substantially ovate in cross section. The closure 40 comprises a cover 41, having a central screw threaded 35 hole and having its rim portion 42 fitted telescopically over the complementary end portion 43, of the tubular casing. Here again, retaining means is provided as at 44. Moreover, the rim portion is provided with segmental slots for exposing the operating ring gear 45. The ring gear is rotatably mounted on the nozzle 46 and rests upon the stop or bearing flange 47. In this form of the invention, I also provide a valve cap 48 swivelly 40 mounted on the exposed portion of the nozzle and provided with a discharge slot 49, registering with the complementary slot 50, in the nozzle. The valve cap is equipped with a finger grip 51. The collapsible container 50 55 is arranged within the casing and cooperates with pressing rollers 53 mounted in the longitudinally movable bearing blocks 54.

Here again, the blocks are threaded on the feed screws 55 mounted for rotation in bearing brackets 56. Moreover, the feed screws are provided at opposite ends with pinions 57 for cooperation with the teeth on the outer periphery of the ring gear 45. It will be noticed from Figure 11 that the feed screws 10 are arranged within the casing as shown for greater compactness and convenience. It is further evident that a removable cap 58 is supplied and is adapted to be replaced by the reversible closure 40. In other words, the closure 40 may be arranged on either end of

the casing, thus making it possible to eject the contents of the container 52 from either end, according to the position of the container within the casing. As before pointed out, this arrangement is advantageous in that it avoids the "feed backs" of the bearing blocks and pressing rollers. In other words, it expedites placement and removal of the collapsible containers. 70

From the description and drawings, it is obvious that I have evolved and produced a novel mechanical device for dispensing cream, tooth paste and the like, from marketed containers, in a convenient and sanitary manner. 75

The invention is simple and inexpensive, 80 and its use will effect economy by squeezing the entire contents from the marketed container.

It is thought that by considering the description in connection with the drawings, 85 a clear understanding of the construction, operation and features of the invention will be had. Therefore, a more lengthy description is regarded as unnecessary.

Minor changes in shape, size, and rearrangement of parts coming within the field of invention claimed may be resorted to, in actual practice if desired. 90

I claim:

1. In a dispensing device of the class described, a casing adapted to encase a collapsible container of the class described, said casing being open at its opposite ends, removable and interchangeable closures for said ends, means in said casing for compressing the container to eject its contents, and operating means for said first named means including an actuating element carried by one of said closures. 95

2. A dispensing device of the class described comprising a casing adapted to house a collapsible container of the type specified, a pair of feed screws mounted for rotation in said casing, a valved nozzle carried by said casing and constructed to permit said container to be releasably connected thereto, and manually manipulated operating means for said feed screws together with separate means mounted on said feed screws and provided with pressing rollers cooperable with 100 said container. 105

3. In a dispensing device of the class described, a casing, a discharge nozzle carried by the casing, a collapsible container in said casing connected with said nozzle, a pair of longitudinally disposed feed screws mounted for rotation in said casing on opposite sides of said container, manually manipulated means on the container for operating the screws, bearing blocks mounted on said screws for longitudinal movement within the casing, and compressing rollers carried by said blocks and cooperable with said collapsible container for squeezing the contents therefrom into and through said nozzle. 120 125 130

4. In a dispensing device of the class described, a casing, a pair of feed screws mounted for rotation in said casing and provided at one end with pinions, a removable closure unit on one end of the casing including a valved discharge nozzle, and a manually rotated ring gear meshing with said pinions for operating said feed screws, together with bearing blocks threaded on said feed screws and located within said casing and provided with pressing rollers.

5. In a dispensing device of the class described, a casing open at one end and adapted for reception of a collapsible container of the type specified, a pair of feed screws mounted for rotation in said casing and provided at one end with operating pinions, bearing blocks threaded on said feed screw, a pair of complemental compressing rollers carried by said blocks, a removable closure for the open end of said casing provided with a valve discharge nozzle and equipped with a rotary finger operated ring gear having operating connection with said pinion.

6. In a dispensing device of the class described, a casing constructed for reception of a collapsible container of the class described, a pair of longitudinally disposed feed screws mounted for rotation in said casing, blocks mounted on said feed screws for longitudinal movement, a pair of complemental compressing rollers positioned in said blocks, said feed screws being provided at one end with pinions, a removable closure fitted telescopically on one end of the casing, a valved nozzle carried by said closure and constructed to permit the conventional screw threaded neck of the collapsible container to be releasably connected therewith, and rotary ring gear carried by said closure and having operating connection with said pinions.

7. In a dispensing device of the class described, an open ended hollow casing adapted to receive a collapsible container of the class described, a pair of feed screws disposed longitudinally in said casing and mounted for rotation therein, pinions on opposite ends of said feed screws extending beyond the opposite open ends of said casing, a removable cap on one end of the casing, a removable closure on the opposite end of the casing, said cap and closure being interchangeable, said closure being provided with a valved nozzle, and being further equipped with a rotary ring gear for operative connection with the pinions at either end of the casing.

In testimony whereof I affix my signature.
RICHARD L. CORNELIUS.
